(57) CLAIM

The ornamental design for a humidification device, as shown and described.

DESCRIPTION

FIG. 1 is a front perspective view of a humidification device, illustrating our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an exploded view of the humidification device of
FIG. 1.

The broken lines in the drawings depict portions of the humidification device that form no part of the claimed design.
